THREADER

Filed April 9, 1929

Inventor
J. F. Klatt

By *Watson E. Coleman*
Attorney

UNITED STATES PATENT OFFICE

JOSEPH F. KLATT, OF PORTLAND, OREGON

THREADER

Application filed April 9, 1929. Serial No. 353,732.

This invention relates to sewing accessories and pertains particularly to an improved needle threading device.

The primary object of the present invention is to provide, in a manner as hereinafter set forth, a device for facilitating the threading of a needle.

Another object of the invention is to provide a means whereby the thread may be conveniently moistened to be rolled into a point for the purpose of facilitating the extension of the point through the eye of a needle.

While the present device may comprise a unit independent of other sewing accessories it is designed primarily to form a part of the sewing kit set forth in detail in my co-pending application No. 353,731, filed April 9th, 1929.

The invention will be best understood from a consideration of the following detailed description taken in connection with the accompanying drawing forming a part of the present invention with the understanding, however, that the invention is not confined to any strict conformity with the showing of the drawing but may be changed or modified so long as such changes or modifications mark no material departure from the salient features of the invention as expressed in the appended claims.

In the drawing:—

Figure 1 shows the device embodying the present invention, in side elevation and mounted upon the upper end of the casing of the above referred to sewing outfit.

Figure 2 is a sectional view taken substantially upon the line 2—2 of Figure 1.

Figure 3 is a top plan view partly in section of the structure shown in Figures 1 and 2.

Figure 4 is a sectional view taken upon the line 4—4 of Figure 3.

Referring to the drawing in detail the numeral 1 indicates generally a base for a needle threading device, the same being here shown in the form of a cap having extending downwardly therefrom the internal threading flange 2 which is designed to engage upon the upper end of the casing of my complete

outfit, a portion of which casing is indicated by the numeral 3.

Mounted upon the top of the cap or base of the needle threader, extending transversely and to one side of the center thereof, is a double walled structure 4 open at each end as shown and covered across the top as indicated at 5. Packed between the sides of the double walled structure is a suitable material 6, such as cotton, hair or the like, into which needles or pins may be extended. Formed transversely through the structure 4, through each side thereof are the openings 7 and mounted upon the base 1 at the opposite side thereof is a post 8 having a passage 9 formed therethrough, the longitudinal axis of which is in alignment with the center of the openings 7. This side of the post remote from the structure 4 is provided with a transverse recess 10 which extends thereacross at the outer end of the passage 9 in the manner shown.

Formed across the top of the post 8 is a pair of grooves 11 the end edges of which are sharpened to provide a thread cutter.

Interposed between the double walled structure 4 and the post 8 is a casing or post 12, the top 13 of which is provided with a pair of apertures 14 and within the post 12 a pair of sponges 15 is placed, each being exposed through one of the openings 14 in the manner shown.

In the use of the needle threading device, a needle is first inserted through the passage 9 toward the opening 7 in the structure 4 and the point is passed into the filling of the structure 4 until the eye of the needle is positioned in the recess 10 of the post in the manner shown in Figure 4. The end of the thread which is to be attached to the needle may then be moistened upon the exposed portion of one of the sponges 15 to facilitate the forming of the same into a point, and the pointed end thereof is then passed along the recess or groove 10 by which it will be guided through the eye of the needle. A needle 16 is shown in position in Figure 4.

Having thus described my invention, what I claim is:—

1. A needle threader comprising a base, a post carried by the base having an aperture

formed transversely therethrough and a recess formed transversely of one end of the aperture, and means associated with the post for supporting one end of a needle positioned in the passage, said supporting means being mounted on the base in spaced relation to the post.

2. In combination in a needle threader, a base, a post carried by the base and having a needle receiving passage therethrough and a thread guide groove formed transversely of one end of the passage, and an upright member carried by the base having an aperture in alignment with said passage and designed to receive the end of a needle lying in the passage.

3. In combination in a needle threader, a base, a post carried by the base and having a needle receiving passage therethrough and a thread guide groove formed transversely of one end of the passage, an upright member carried by the base having an aperture in alignment with said passage and designed to receive the end of a needle lying in the passage, and a thread moistener device carried by the base.

4. A needle threader comprising a base, a hollow walled structure carried by the base and having a passage formed transversely therethrough, a soft filling material in said structure exposed through said passage, a post mounted upon the base on one side of the wall and having a needle receiving passage formed therethrough in alignment with said wall passage, and a recess formed transversely thereof at the side remote from the wall and across the adjacent end of the needle receiving passage.

In testimony whereof I hereunto affix my
40 signature.

JOSEPH F. KLATT.
